ELECTRICAL STRAIN INSULATOR OR
SIMILAR ARTICLE

Fred C. Vose, Severna Park, Md., assignor to General
Electric Company, a corporation of New York

Filed Jan. 8, 1968, Ser. No. 10,080

Term of patent 14 years

Int. Cl. D13—03
U.S. Cl. D26—10

Fig. 1.

Fig. 2.

Fig. 3.

Fig. 4.

FIG. 1 is a side elevation view of an electrical strain insulator or similar article showing my new design, the opposite side being substantially a mirror image thereof;

FIG. 2 is an end elevation view, showing the clevis end thereof.

FIG. 3 is a side elevation view of an electrical strain insulator or similar article as would be seen from the right of FIG. 1 showing a modification of my new design, the opposite side being substantially a mirror image thereof; and

FIG. 4 is an end elevation view, showing the tongue end thereof;

I claim:

The ornamental design of an electrical strain insulator or similar article, as shown and described.
